(57) **CLAIM**

I claim the ornamental design for a portable steaming device, as shown and described.

DESCRIPTION

FIG. 1 is a perspective view of a portable steaming device embodying the present invention;

FIG. 2 is a front elevational view thereof;

FIG. 3 is a rear elevational view thereof; and

FIG. 4 is a left side elevational view thereof;

FIG. 5 is a right side elevational view thereof;

FIG. 6 is a bottom view thereof; and,

FIG. 7 is a top plan view thereof.

The broken line structure shown in FIGS. 3-7 is for illustrative purposes only and forms no part of the claimed design.
